UNITED STATES PATENT OFFICE

IRVIN F. DITTMAR, OF WILLIAMSPORT, PENNSYLVANIA, ASSIGNOR TO THE CROMAR CO., OF WILLIAMSPORT, PENNSYLVANIA, A CORPORATION OF PENNSYLVANIA

GUIDE FOR STRIP FINISHING MACHINES

Application filed December 7, 1928. Serial No. 324,348.

My invention relates to improvements in strip finishing machines.

The object of my invention is to provide an improved guide for a strip finishing machine, whereby the strips of flooring are guided more accurately in their rapid passage through the machine and providing means whereby one of the guides can be swung outwardly and upwardly for removing the strips in the event they become jammed for any reason whatever.

Another object of my invention is to provide an improved guide for strip finishing machines in which an adjustable means is provided for the rigid or lower guide so that it can be adjusted vertically in respect to the upper guide to allow strips of flooring of different width to pass through the machine or take up any wear of the guides.

A further object of my invention is to provide a simple, cheap and effective arrangement of the movable upper guide and a vertically adjustable stationary lower guide and said arrangement having certain details of structure and combination of parts hereinafter more fully set forth.

In the accompanying drawings:

Figure 1 is an end view of a floor finishing machine showing my improved guides applied thereto.

Figure 2 is a side elevation of Figure 1 showing the cleaning brushes.

Figure 3 is an edge view of the plate upon which is mounted the upper guide operating mechanism.

Figure 4 is a front elevation of Figure 3.

Figure 5 is a top plan view of Figure 4.

Figure 6 is an edge view of the lower guide supporting plate.

Figure 7 is a front elevation of Figure 6.

Figure 8 is a top plan view of Figure 7.

Figure 9 is a perspective view of the block for locking in position the plates which hold the lower guide rail in position against lateral movement.

Figure 10 is a side elevation of the member for supporting and pivotally mounting the upper guide rail to the member shown in Figure 4 of the drawings.

Figure 11 is an end view of Figure 10.

Figure 12 is a top plan view of one of the plates for holding the lower guide rail in position.

Figure 13 is a side elevation of Figure 12.

Figure 14 is a plan view of another plate arranged beyond the plate shown in Figure 12 for holding the lower guide rail in position.

Figure 15 is a side elevation of Figure 14.

Figure 16 is a sectional view taken on the line 16—16, Figure 15.

Figure 17 is a sectional view taken on the line 17—17, Figure 15.

Figure 18 is an end view of Figure 15.

Figure 19 is a perspective view of one of the plates employed for bracing and supporting the upper guide member.

Figure 20 is a detached perspective view partly broken away showing a strip of flooring in dotted lines between the upper and lower guide members.

Figure 21 is a side elevation of the lever for swinging the upper guide member.

Figure 22 is an edge view of Figure 21.

Referring now to the drawings, 1 represents the base of an ordinary strip finishing machine, and upon which is secured, by means of bolts 2 and 3, the upwardly extending plate or frame 4 having at its upper end the enlarged head portion 5 having a rectangular groove 6 extending from end to end thereof. The head portion 5 at one side is provided with an outwardly extending arm 7 having a horizontally arranged opening 8 therein, adjacent the head, and the outer end of said arm having a vertically disposed screw threaded opening 9, therethrough the purpose of which will be hereinafter more fully described.

Mounted on the head portion 5 of the plate or frame 4 is an upwardly extending plate 10 having outwardly extending ears 11 and 12 at its lower end and provided with openings through which bolts 13 and 14 pass, and said bolts screwed into the openings in the ears 15 and 16 carried by the outer face of the head 5 of the plate or frame 4, whereby the member 10 is rigidly supported by the member 4 in the position shown in Figure 1 of the drawings.

Within the rectangular recess 6 of the head 5 is the lower guide member 17, and arranged

on each side thereof within the recess 6 is the 5 guide member holding plate 19 which abuts against the vertical faces of the guide and hold it in its vertical position. The plate 19 is locked in position by the blocks 20, as clearly shown in Figure 7 of the drawings. Mounted within the horizontal opening 8 of the arm 7 is a pin or shaft 21 carried by a lever 22 intermediate its ends and whereby 10 said lever is intermediately pivoted on the arm 7. The inner end 23 of the lever 22 extends under the guide member 17 and serves as a support for the same, and a number of levers are provided for supporting the guide 15 at several points. The opposite end of the lever 22 extends out over the opening 9 in the arm 7 and is provided with a bolt 24 adapted to screw into the threaded opening 9 of the arm 7. By this structure it will be 20 seen that the lower guide member 17 may be raised or lowered in respect to the upper guide member by turning the bolt 24, as clearly shown in Figure 1 of the drawings.

The upper end of the plate 10, as shown in 25 Figures 1 and 4 of the drawings, is provided with an outwardly extending pin 25 which extends in a horizontal line and passes through an elongated opening 26 in the operating lever 27. The lever 27 extends in an 30 oblique direction and passes between the arms 28, carried by the upper end of the member 10 and is guided thereby. The lever 27 has a reduced rounded portion 29, and surrounding the same is a coil spring 30 which bears 35 against a block 31 sliding on the reduced portion of the lever, whereby said block frictionally engages the arms 28 and holds the lever in its adjusted position. The member 10 on its inner face is provided with a boss 32 40 through which passes a set screw 33 adapted to engage the enlarged portion of the lever 27, as clearly shown in Figure 1 of the drawings, for limiting the movement of the lever. The lower end of the lever 27, below the pivot 45 25, extends in an oblique direction and is provided with the laterally turned end 34 adapted to enter the opening 35 in the block 36. The block 36 is pivotally mounted at 37 upon the pin 38 carried by the plate 10. The block 50 36 is provided with a downwardly extending arm 39 having an opening 40 therein into which is screwed a bolt 41, said bolt is also screwed into the upper guide member 42, whereby this guide member is pivotally supported by the block 36. A number of blocks 55 36 are provided whereby the guide member is supported at several points.

The guide member 42, as clearly shown in 60 Figure 20 of the drawings, is made in two sections 43 and 44 secured together in any desired manner, as this has been found to be the most practical way of making the same.

Arranged beside the guide member 42 is a 65 plate 45 which serves as a stop and brace for the guide member 42, limiting its move-

ment in one direction but allowing it to be swung outwardly in the opposite direction.

From the foregoing description it will be seen that should a strip of flooring become jammed in the machine between the upper 0 guide member 42 and the lower guide member 17, the lever 27 is moved, causing the laterally turned end 34 to move the block 36 on its pivot 37 and swing the upper guide member outwardly and upwardly so that the strip of flooring can be removed from the machine. In this movement of the lever, the spring 30 is holding the block 31 against the plates 28 and when the lever is released the lever will be held in its position so that the upper guide member is held in its upward position. The spring 30 also holds the lever in its position so that the upper guide member is held in its vertical operative position but when undue pressure is exerted thereon it may swing upwardly and outwardly. 85

The plate 10, as shown in Figure 4 of the drawings, is made so that the lever can be mounted to operate from either the right or left side of the machine. It will be understood that there is a block 36 and a lever 27 and the other end of the upper guide member 42 operated in precisely the same manner as the lever 27, shown in Figure 1 of the drawings. 95

While in the specification I have described my invention as especially adapted to be used for finishing strips of flooring, it is, of course, understood that the same can be used in connection with any guiding means for guiding 100 strips of lumber of any kind.

Having thus fully described my invention what I claim is:—

1. A guide for strip finishing machines comprising a pair of spaced guide members 105 between which the strip to be finished is adapted to pass longitudinally in its passage therethrough, the upper guide member being hinged to swing upwardly and outwardly in one direction, and a pivoted and slidably mounted lever for operating said swinging guide member.

2. A guide for strip finishing machines comprising superposed guide members between which the strip is adapted to pass longitudinally in its passage therethrough, the upper guide member being adapted to swing outwardly and upwardly, and a pivoted and slidably mounted lever cooperating with the hinged member for swinging the upper guide 115 member. 120

3. A guide for strip finishing machines comprising a lower guide member, means for adjusting said guide member vertically, a sectional upper guide member hinged to swing outwardly and upwardly in one direction, and a pivoted and slidably mounted lever for swinging said guide member. 125

4. A guide for strip finishing machines comprising a lower guide member, inter- 130

mediately pivoted levers supporting said guide member, means for adjusting said levers for moving the guide member vertically, an upper guide member above the lower guide member and a pivoted and slidably mounted operating lever for swinging said upper guide member upwardly and outwardly.

5. A guide for strip finishing machines comprising a lower guide member, pivoted levers supporting the guide members, means for adjusting said levers for moving the guide member vertically, an outwardly and upwardly swinging guide member above the lower guide member and a pivoted, slidably and yieldably mounted lever for moving said guide member and yieldably holding said guide member in its proper position.

6. A guide for strip finishing machines comprising a guide member, intermediately pivoted levers supporting the guide member on one end, a bolt for adjusting the opposite ends of the levers and vertically adjusting the guide member, an outwardly and upwardly swinging guide member above the lower guide member and a pivoted and slidably mounted lever for moving said upper guide member.

7. A guide for strip finishing machines comprising a lower guide member, means for vertically adjusting the said guide member, an outwardly and upwardly swinging guide member above the first mentioned guide member, and a pivoted and slidably mounted lever adapted to cooperate with the swinging guide member for moving it upwardly and outwardly.

8. A guide for strip finishing machines comprising a lower guide member, a swinging guide member above the lower guide member and adapted to swing outwardly and upwardly, a lever for operating the swinging guide member, and friction means cooperating with the lever for holding the upper guide member in its upwardly or vertically operative position.

9. A guide for strip finishing machines comprising a lower guide member, pivoted blocks above the lower guide member, a second guide member rigidly carried by said blocks, a pivoted lever cooperating with one of said blocks for swinging it on its pivot to move the guide member outwardly and upwardly, and friction means for holding the lever with the upper guide member in its upwardly or vertically operative position.

10. A guide for strip finishing machines comprising a lower guide member, pivoted means for adjusting said guide member vertically, a swinging guide member having the lower guide member, means for swinging said upper guide member and friction means for holding the upper guide member in its upward or vertical operative position.

11. A guide for strip finishing machines comprising a lower guide member, means for

adjusting said guide member vertically, an upper swinging guide member adapted to swing outwardly and upwardly in one direction, means for swinging said guide member, and yielding means for holding the upper guide member in its upward or vertical operative position.

12. A guide for strip finishing machines comprising a lower guide member, means for vertically adjusting said guide member, an upper guide member hinged to swing outwardly and upwardly in one direction, a lever having an operative connection with the hinge of the upper guide member, means for limiting the movement of the upper guide member in one direction and yielding means for holding the upper guide member in its upward or vertically adjusted operative position.

13. A guide for strip finishing machines comprising a lower guide member, intermediately pivoted levers having their inner ends supporting the guide member, means for adjusting the outer ends of the lever for vertically moving the guide member, a hinged guide member above the lower guide member and adapted to swing outwardly and upwardly in one direction and prevented from moving in the opposite direction, means for swinging said guide member and yielding means for holding the guide member in its upward or vertically adjusted operative position.

14. A guide for strip finishing machines comprising a pair of horizontally disposed guide members through which the strip is adapted to pass longitudinally in its passage therethrough, a pivoted and slidably mounted lever for moving the upper guide member vertically and laterally in respect to the lower guide and a spring pressed element for holding said lever in adjusted position.

15. A guide for strip finishing machines comprising a pair of guide members between which the strip is adapted to move longitudinally in its passage therethrough, means for adjusting the lower guide member, a pivoted and slidably mounted lever for moving the upper guide member vertically and laterally in respect to the lower guide member and frictional means for holding said lever in adjusted position.

16. A guide for strip finishing machines comprising a pair of horizontally disposed spaced guide members between which the strip is adapted to pass to be finished, one of said members being movably mounted to first move in a vertical plane and then in a lateral plane and spring actuated means for holding said guide in raised and lowered position.

17. A guide for strip finishing machines comprising a pair of spaced guide members, one of said members being adjustably mounted in respect to the other member and adapted to swing outwardly and upwardly in one di-

rection, a block pivotally mounted to one side of said guide members having a connection with the adjustably mounted guide member and a pivoted and slidably mounted lever connected to said block.

18. A guide for strip finishing machines comprising a pair of superposed guide members between which the strip is adapted to pass in its passage through said machine, means for adjusting the lower guide member vertically and a pivoted and slidably mounted lever for swinging the upper guide member vertically and laterally above the lower guide member.

15 In testimony whereof I hereunto affix my signature.

IRVIN F. DITTMAR.
